UNITED STATES PATENT OFFICE

137,052

DESIGN FOR A CORSAGE OR SIMILAR ARTICLE

Robin C. Jacobson, Evanston, and Hermann
Leistner, Chicago, Ill.

Application November 12, 1943, Serial No. 111,668

Term of patent 14 years

To all whom it may concern:

Be it known that we, Robin C. Jacobson and Hermann Leistner, citizens of the United States and residents of the city of Evanston and the city of Chicago, respectively, county of Cook and State of Illinois, have invented a new, original, and ornamental Design for a Corsage or Similar Article, of which the following is a specification, reference being had to the accompanying drawing, forming a part thereof.

Fig. 1 is a front elevational view of a corsage or similar article, showing our new design; and Fig. 2 is a back view thereof.

We claim:

The ornamental design for a corsage or similar article, as shown.

ROBIN C. JACOBSON.
HERMANN LEISTNER.
